UNITED STATES PATENT OFFICE.

HEINRICH BURCHARTZ, OF GELSENKIRCHEN, GERMANY, ASSIGNEE TO GELSEN-KIRCHENER BERGWERKS-AKTIENGESELLSCHAFT, OF GELSENKIRCHEN, GERMANY.

CENTRIFUGAL CASTING MACHINE.

Application filed January 29, 1925. Serial No. 5,517.

To all whom it may concern:

Be it known that I, HEINRICH BURCHARTZ, a citizen of the German Republic, and a resident of Gelsenkirchen, Germany, have 5 invented certain new and useful Improvements in Centrifugal Casting Machines, of which the following is a specification.

This invention relates more especially to centrifugal casting machines such as that 10 shown in German Patent No. 378,557, Ausgegeben July 20, 1923, and has for its object to provide an improved construction, combination and arrangement of parts in the core-inserting mechanism of casting machines of this character whereby the core-inserting plunger may be moved out of close 15 juxtaposition to the rotary mold to permit a core to be mounted thereon with greater facility.

20 More specific objects of invention will appear in the specification and be pointed out in the claims in connection with the drawings which show a preferred embodiment of the invention.

25 In the drawings—

Figure 1 is a side elevation of one embodiment of my invention, parts being broken away and parts shown in section; and

30 Figure 2 is a side elevation of a modification according to which the core-carrying plunger is revolvable in a horizontal plane instead of in a vertical plane as shown in Figure 1.

With reference to these drawings, it will 35 be understood that while Figure 1 shows a core-carrying plunger which swings in a vertical plane and Figure 2 shows said plunger movable in a horizontal plane, these two movements may be readily combined in 40 a single machine so that either of said swinging movements may be accomplished or both together.

The above identified German patent 45 contemplates mechanism for inserting flange-cores together with flange-core plates into the molding chambers of centrifugal machines for casting pipe or other hollow bodies. According to said patent, the core-holding plunger is reciprocably mounted in 50 a suitable bearing or pedestal, said bearing being arranged on a fixed axis which coincides with the axis of the rotary molding chamber. Difficulty has been experienced in 55 the use of machines of this nature due to the fact that in order to mount the cores up-

on the reciprocable plunger, they must first be interposed between said plunger in its retracted position and the end of the rotary mold. The available space for handling the cores is thus more or less limited 60 so that this difficulty increases with the size of the core. In order to overcome these drawbacks, the present invention contemplates a core inserting mechanism according to which the reciprocating plunger is moved 65 out of its operative position with respect to the rotary molding chamber before the core is mounted thereon. In the preferred embodiment of my invention shown on the drawings, the plunger is suitably mounted 70 to convey a core to and from the mold but at the same time is adapted to be swung about either or both of two different axes to remove it from the mold before and after its reciprocatory movement with respect 75 thereto.

The embodiment of my invention shown in Figure 1 contemplates a core-carrying plunger 1 provided below with a rack 2 which is driven by a pinion 3, said pinion 80 being non-rotatably mounted with respect to a gear 4 which meshes into a pinion 5 carried by a horizontal shaft to which is secured an operating hand wheel 6. Pivotally mounted in the outer end of the core-carrying plunger 1, are three equi-spaced 85 radially movable segments 7, which are adapted to engage the inner cylindrical wall of the pipe-mold for centering the plunger with respect thereto. Each of said segments is non-rotatably connected to a gear 8, in mesh with a rack 9 carried by a reciprocatory rod 10. As shown on the drawings, the reciprocatory rod 10 is slidably supported within the plunger 1 and may be 90 reciprocated at will by a hand lever 11. The segments 7 are thus adapted to be moved in unison. A flange core 12 removably seated upon the plunger 1 is thus truly centered 95 with respect to the mold within which it is to be set up.

In order to provide suitable means whereby the plunger 1 may be moved out of juxtaposition to the centrifugal mold for mounting the core thereon preparatory to its placement in the mold, said plunger 1 is mounted to slide in a bearing 13 which is movable to and fro between full line and dotted line positions shown in Figure 1. For this purpose, bearing 13 is pivotally mounted in a 110

pedestal 14 upon an axis 15. It will be seen that when the parts are in dotted line position shown in Figure 1, the core-carrying end of plunger 1 is well removed from the centrifugal mold and readily accessible for mounting a core thereon or removing it therefrom. This operation may be performed by hand or any suitable hoisting device (not shown).

10 Referring now to the embodiment of my invention shown in Figure 2, the construction and arrangement of parts are substantially similar to that shown in Figure 1 except the movement of the core-carrying plunger to and from juxtaposition to the centrifugal mold. The bearing 16 within which the core-carrying plunger is slidably mounted in this embodiment, is provided with a downwardly presented shaft 17 which 15 swivels on a vertical axis within a bearing 18 with which the pedestal 19 is provided.

I claim:

1. The combination with a centrifugal casting machine, of means movable axially thereof for inserting cores into said machine, and removing them therefrom, said means being movable transversely to said axis for mounting said core on said inserting means and removing said core therefrom.
2. The combination with a centrifugal casting machine, of mechanism for insert-

ing a core into a centrifugal casting machine, said mechanism comprising a core-holding plunger movable axially for inserting and removing a core, said plunger being movable transversely to its core-inserting movement into and out of position to receive a core.

3. The combination with a centrifugal casting machine, of a core-holding plunger movable endwise to convey a core into and out of position within said machine, said plunger being movable about an axis transverse to its own axis to a position in which a core may be mounted thereon or removed therefrom.

4. The combination with a centrifugal casting machine, of a core-holding plunger reciprocable endwise and movable about different axes into and out of coaxial alignment with the axis of rotation of said centrifugal casting machine.

5. The combination with the rotary member of a centrifugal casting machine, of a core-holding plunger suitably mounted to swing in two different planes into and out of coaxial alignment with the rotary axis of said rotary member, and means for imparting an endwise reciprocatory movement to said plunger.

HEINRICH BURCHARTZ.
